WATER CONTROL HANDLE FOR BATH AND SHOWER

James A. Tiller, Decatur, Ga., assignor to American Standard Inc., New York, N.Y., a corporation of Delaware

Filed Dec. 10, 1969, Ser. No. 20,434

Term of patent 14 years

Int. Cl. D23—01

U.S. Cl. D23—31

FIG. 1

FIG. 2

FIG. 3

FIG. 4

FIG. 1 is a top perspective view of a water control handle for a bath and shower embodying the new design;
FIG. 2 is a rear view thereof;
FIG. 3 is a side view thereof; and
FIG. 4 is a top view thereof.

I claim:

The ornamental design for a water control handle for bath and shower, substantially as shown.
